UNITED STATES PATENT OFFICE.

HENRY WILLIAM GRELLE, OF NEW ORLEANS, LOUISIANA, ASSIGNOR OF
TWO-THIRDS TO FRANK J. KOERNER AND GEORGE W. BYRNE, JR., OF
SAME PLACE.

WATER-FILTER.

SPECIFICATION forming part of Letters Patent No. 381,067, dated April 10, 1888.

Application filed September 6, 1887. Serial No. 242,979. (No model.)

To all whom it may concern:

Be it known that I, HENRY WILLIAM GRELLE, a citizen of the United States, residing at New Orleans, in the parish of Orleans and State of Louisiana, have invented certain new and useful Improvements in Water Filters; and I do declare the following to be a full, clear, and exact description of the invention, such as will enable others skilled in the art to 10 which it appertains to make and use the same.

This invention relates to filters; and the improvements will be fully understood from the following description and claims, when taken in connection with the annexed drawings, in 15 which—

Figure 1 is a perspective view of my improved filter. Fig. 2 is a vertical sectional view of the same, with the upper pure-water chambers broken away; and Fig. 3 is a vertical sectional view of one of the pure-water chambers, showing the pipes for connecting the same with the filtering-chamber.

Referring by letter to the said drawings, A indicates the main chamber, which may be of 25 any suitable capacity and form, and into which the water to be filtered is introduced, as will be presently explained. This chamber is reduced to a concentric water-chamber, a, by placing therein a central chamber, B, which 30 is filled with sand or other filtering material. The chamber B is composed of a perforated shell, the roof of which is also perforated, as shown at b. The concentric water-chamber a is provided with an inlet-aperture, c, for the 35 introduction of impure water, and also an aperture, d, for the outlet of mud and sediment. The central filtering-chamber, B, is also provided with a capped aperture, e, for the introduction of sand or the like. It will thus be 40 seen that when it is desirable to clean out the main water-chamber a it is only necessary to remove the cap from the opening d and let water in under pressure through the aperture c, when the mud will be effectually removed 45 and expelled therefrom.

D is an auxiliary filtering-chamber, which is arranged above the central base-chamber, B, and has a capped opening, f, for the introduction of sand or the other filtering-material, as

shown. This chamber D is preferably of dome 50 shape, and has a pipe, g, leading from its top, which communicates with a branched pipe, E, leading, respectively, to two clear-water chambers, as will be presently described. As the chambers F F are similar in construction, a 55 description of one will suffice for both. The forked or branched pipe E communicates with the bottom of the chambers, and within the said chambers, above and surrounding such communication, is formed a smaller chamber, 60 h, which is divided by a horizontal perforated partition, k, so as to form an upper cotton-chamber, G. H is a movable perforated top for the cotton-chamber. This top has swiveled to it the lower end of a vertical threaded 65 rod, I, to the upper end of which is fixed a hand-wheel, K. This vertical shaft or rod has its bearing in a screw-tapped cross-bar, L, placed across the mouth of the said chamber G. Thus it will be seen that the cotton M in 70 the said chamber may be compressed by simply turning the hand-wheel of the vertical shaft. It will also be seen that the chamber F is divided into a cotton-chamber and also a surrounding clear-water chamber, N, from 75 which latter leads a branched pipe, P, having a cock or faucet, R, arranged about midway of its length. The chambers F are provided with suitable covers, which are held closed by a cross-bar, l, and set-screws, as shown. 8c

In operation, sand, gravel, or other suitable filtering material is placed in the chambers B and D, and cotton in the chamber G. The water to be filtered being now let in under pressure to the concentric water-chamber a, it 85 will gradually pass, by way of the perforated walls of the central chamber, B, through the sand therein and thence through the filtering material in the chamber D, after which it will pass through the pipe g and branch pipe E to 90 the cotton-chamber G, which latter pass will thoroughly filter the water, and after the same passes over the top of these cotton-chambers and descends into the clear-water chambers it 95 may be drawn off for use at the cock of the branched pipe P.

Having described my invention, what I claim is—

The combination, with the concentric water-chamber having apertures, as described, of the central perforated filtering-chamber arranged therein, the filtering-chamber arranged 5 above the central chamber and having the pipe leading from its top, the cotton-chambers having perforated bottoms and a perforated compressing-top, the clear-water chambers surrounding the cotton-chambers and communicating therewith, the pipes connecting the cot-

ton-chambers with the filtering-chambers, and the draft-pipes leading from the clear-water chambers, substantially as specified.

In testimony whereof I affix my signature in presence of two witnesses.

HENRY WILLIAM GRELLE.
